UNITED STATES PATENT OFFICE

EUGENE E. AYRES, JR., OF SWARTHMORE, PENNSYLVANIA, ASSIGNOR TO THE B. A. S. COMPANY, OF PHILADELPHIA, PENNSYLVANIA, A CORPORATION OF DELAWARE

PROCESS OF PRODUCING ALCOHOLS FROM GASOLINE

No Drawing.

Application filed September 14, 1925. Serial No. 38,410.

My invention relates to processes for the production of butyl and amyl alcohols from gasoline derived from natural gas.

It is an object of the present invention to provide a process whereby alcohols of the type ordinarily employed for the production by acetylation of commercial solvents for nitrocellulose, may be synthesized from a relatively inexpensive source of raw material. A further object of my invention is to provide a process wherein the by-products have commercial value.

In the practice of my invention the source of the raw material, namely, gasoline obtained from natural gas, is divided by rectification into certain fractions. The first fraction, composed of lower boiling hydrocarbons, is not utilized in the present invention, said low boiling hydrocarbons not being valuable for purposes of synthesis of alcohols that are sought by this process nor as a constituent in gasoline. The second and third fractions I use as a source of raw material in my process of forming alcohols, these two fractions respectively resulting in different forms of alcohols in the final step of the process.

The rectification is accomplished by refluxing isobutane during the separation of the first fraction. If it is desired to handle the butane and pentane fractions separately it is necessary to reflux normal butane while obtaining the second fraction and to reflux normal pentane while obtaining the third fraction. On the other hand, if it is desired to handle the butane and pentanes together, as for the purpose of reducing the number of rectifying columns in a continuous system, the refluxing of normal butane need not be carefully carried out but in every case normal pentane is refluxed to prevent the carrying over of higher boiling hydrocarbons.

The residue, after the separation by either of these operations of the three fractions above mentioned, comprises a useful form of gasoline, especially adapted to use as airplane fuel, as dry cleaner's benzine, or as a solvent in the rubber industry. In accordance with my invention I can adjust the initial and end boiling points of this product to

meet trade requirements or specifications which may be imposed. The fractions which I have designated respectively as second and third are then subjected to chlorination by heating with chlorine and the chlorine substitution products are converted by hydrolysis into the desired alcohols, as by means of processes set forth in co-pending applications hereinafter set forth.

In the first step of my process, natural, or casinghead, gasoline is subjected to fractional distillation in a rectifier. I separate as a first fraction all those lighter hydrocarbons having higher volatility which are not useful in gasoline and which do not form alcohols of the type herein contemplated. But while I prefer to use these hydrocarbons for their fuel value in the preferred form of my invention, I merely suggest this as a convenience and do not intend that my invention shall be limited to such a procedure. The first fraction separated off is composed principally of propane and isobutane. The second fraction separated off comprises principally normal butane. The third fraction contains chiefly pentane and isomers thereof. After the separation of the above mentioned fractions the residual liquid, is composed largely of hexane and its isomers with a small percent of higher boiling hydrocarbons.

The fractions which I utilize for the purpose of making alcohols are those which I have designated respectively as "second" and "third" above, that is, the fractions which may be designated as the butane and the pentane fractions, it being understood that in each case the fraction is not composed of a pure substance but contains many substances, including isomers. The butane and pentane fractions may then be treated in accordance with the succeeding steps of my process either separately or in mixture. If treated separately the resulting alcohols are respectively butyl and amyl alcohols; if treated in mixture, the resulting alcohols are a mixture of butyl and amyl alcohols.

In effecting the above described separations of the gasoline into these fractions, the distillation may be run continuously or discontinuously, under a pressure that is high

- enough that condensation for purposes of rectification reflux may be readily performed. Inasmuch as the boiling points of butane and pentane at various pressures are well known, being shown in the Wilson & Bahlke chart appearing at page 116, of volume 16, No. 2, of Industrial and Engineering Chemistry, for February 1924, and in the chart appearing at page 32-C of National Petroleum News, for April 8, 1931, the pressure employed while distilling off the normal butane and the pentane fractions can be chosen to suit the temperature of the condensing medium available. Even in summertime when cooling water for condensers is not readily maintained at a low temperature, it will be observed that the pentane fraction may be distilled at a gage pressure of 25 lbs. per square inch at which its boiling point is in the neighborhood of 155° F. and the normal butane fraction may be distilled at a gage pressure in the neighborhood of 75 lbs. per square inch at which its boiling point is in the neighborhood of 140° F. When the normal butane fraction is collected separately from the pentane fraction, the reflux substance must contain butane, while the butane is being taken off, and must contain pentane while the pentane is being taken off.
- The rectification may be so conducted as to obtain practically ninety nine percent purity of the butane and pentane fractions but it is sufficient for the purposes of my process to obtain merely a ninety percent purity, this being satisfactory for the succeeding steps which I employ for the synthesis of alcohols.
- The residue, composed mainly of hexane and with traces of higher boiling hydrocarbons, has certain special uses in which its value is enhanced if its initial and end boiling points be accurately adjusted. The initial boiling point of the hexane residue (loosely so-called) may be lowered by leaving in the residue or introducing into it a relatively small quantity of pentane, and thus the initial boiling point of the hexane residue may be adjusted over a range of temperatures. The end boiling point may be adjusted by fractional distillation of the hexane residue in a rectifier to an extent sufficient to separate the hexane from the higher boiling hydrocarbons. In this way the initial and end boiling points of a gasoline comprised almost wholly of hexane may be determined and adjusted and thus a useful commercial article produced as a by-product of my process for the production of alcohols from natural gasoline.
- The butane and pentane fractions are then synthesized into corresponding alcohols, as by the series of steps set forth in co-pending applications hereinafter mentioned. Following the separation of the pentane fraction (which will be used by way of illustra-

tion) the pentane is chlorinated by the action of heat, as distinguished from the action of actinic rays, in order that the proportion of primary monochlorides produced will be relatively large, preferably in accordance with the process, and the apparatus for the practice thereof, disclosed in my Patent No. 1,741,393 issued December 31, 1929. The chlorinated product thus obtained is then hydrolyzed to produce alcohols, preferably in accordance with the process disclosed in Patent No. 1,691,426 issued November 13, 1928, to myself and Erling H. Haabestad.

Alcohols so produced may be purified, preferably by extraction with water, as for example, by the method disclosed in Patent No. 1,716,957, issued June 11, 1929, to Erling H. Haabestad.

Thus, the chlorination of the butane and pentane may advantageously be effected by vaporizing those hydrocarbons and mixing them in excess, e. g. fifteen to twenty parts of hydrocarbon vapor to one part of chlorine gas, and then causing the hydrocarbons and chlorine to react by raising the temperature of the mixture to a temperature between 600° F. and 700° F. Then the products of the chlorinating operation are, before or after separation of the hydrochloric acid, subjected to rectification to recover unchlorinated hydrocarbons as one product and chlorinated hydrocarbons free of unchlorinated hydrocarbons as the other product. Unchlorinated hydrocarbons recovered from the product of the reaction and freed of hydrochloric acid may be returned to the chlorinating operation. The normal butane and pentanes so chlorinated contain an unusually large proportion of primary monochlorides of those hydrocarbons.

And, the chlorine derivatives of normal butane and pentane, so produced, are advantageously hydrolyzed to produce monohydric alcohols containing four to five carbon atoms by converting the chlorine derivatives into esters by heating them with water and a salt of a substantially water-insoluble fatty acid and then completing the hydrolyzation in one of two ways. The organic ester, for example, amyl oleate, may be heated with a hydrolyzing agent, such as caustic soda, producing alcohol and soap. Or, the organic ester may be heated in the presence of water together with additional quantities of the chlorine derivatives and a suitable hydrolyzing agent, such as sodium hydroxide, in which case any soap formed reacts at once to restore or replace the organic ester, and the organic ester, in a sense, acts as a catalyst to effect substitution of hydroxyl radicals for the chlorine atoms of the chlorine derivatives. In such operations the reaction of the chlorine derivative with the soap to produce the organic ester is rapid and complete in spite of the insolubility of the soap.

in chlorine derivatives of hydrocarbons, because of the colloidal contact attained in the operations described; and the production of alcohol is relatively rapid and complete because of the presence of the organic ester, and the product is unusually free of undesirable products because the pressures employed need not substantially exceed the pressures necessary to maintain the final products in liquid form at a temperature of 150° C. in a closed vessel.

And, the purification of the resulting butyl and amyl alcohols or a mixture of them is advantageously effected by water extraction in which a continuous circulation of water is maintained, the water absorbing alcohol at one point of its circulation and alcohol being separated therefrom at another point of its circulation. In such an operation the water is circulated through a body of the crude alcohol and then passed to a still and then returned to the body of crude alcohol. In the still the alcohol-containing water is heated and the vapors contain more alcohol than can be dissolved in the water contained in the vapors. The vapors are condensed and separation of alcohol from water is made by gravity, the condensed water containing whatever alcohol it will dissolve being returned to the still and thus to the body of crude alcohol. The alcohol may be dried by heating and the resulting vapors returned to the condensing operation. The amyl and butyl alcohols are thus freed of such substances as amyl and butyl chlorides and hydrocarbons.

As a specific example of the practice of my invention I have started with 100 gallons of gasoline made from natural gas. Upon rectification it was found that 5 gallons were lost in the first fraction, composed of propane and isobutane. The second fraction, containing normal butane, amounted to 20 gallons; the pentane fraction amounted to 25 gallons; and the hexane residue amounted to 50 gallons. This residue was of a quality and possessed of initial and end boiling points such as to make it suitable for airplane fuel. The butane and pentane fractions were each about 90 percent pure. After chlorination, the 20 gallons of butane yielded 20 gallons of butyl chloride; and the 25 gallons of pentane yielded 24 gallons of amyl chloride. These chlorides were respectively hydrolyzed and after purification yielded respectively 14 gallons of butyl and 16 gallons of amyl alcohols.

More specifically, with respect to the following example of the production of amyl alcohols from pentanes, the chlorination of the character above described, by the action of heat in the absence of actinic rays and the absence of electric discharge, of a mixture of pentanes obtained from natural gasoline and having a boiling range from 28° C. to 36° C.

gives a mixture of chlorides which is difficult to analyze and contains the following substances in approximately the proportions indicated:

23%-27% $\text{CH}_3\text{CH}_2\text{CH}_2\text{CH}_2\text{CH}_2\text{Cl}$	1-chlorpentane	70
15%-18% $\text{CH}_3\text{CH}_2\text{CH}_2\text{CH}_2\text{CH}_2\text{Cl}$	2-chlorpentane	
7%-10% $\text{CH}_3\text{CH}_2\text{CH}_2\text{CH}_2\text{CH}_2\text{Cl}$	3-chlorpentane	
11%-14% $\text{CH}_3\text{CH}_2\text{CH}_2\text{CH}_2\text{CH}_2\text{Cl}$	1-chlor-3-methyl butane	
4%-6% $\text{CH}_3\text{CH}_2\text{CH}_2\text{CH}_2\text{CH}_2\text{Cl}$	2-chlor-3-methyl butane	75
23%-27% $\text{CH}_3\text{CH}_2\text{CH}_2\text{CH}_2\text{CH}_2\text{Cl}$	1-chlor-2-methyl butane	
4%-7% $\text{CH}_3\text{CH}_2\text{CH}_2\text{CH}_2\text{CH}_2\text{Cl}$	2-chlor-2-methyl butane	

and hydrolyzing of that mixture of chlorides by hydrolysis of the character above described in the presence of water and a salt of a substantially water-insoluble fatty acid, produces a mixture of amyl alcohols which is difficult to analyze but contains the following alcohols in approximately the proportions indicated:

Structural formula	Boiling point	Per cent	90
$\text{CH}_3\text{OH}\cdot\text{CH}_2\cdot\text{CH}_2\cdot\text{CH}_2\cdot\text{CH}_2\cdot\text{CH}_3$	138° C.	26-29	
$\text{CH}_3\text{CHOH}\cdot\text{CH}_2\cdot\text{CH}_2\cdot\text{CH}_2\cdot\text{CH}_3$	119° C.	16-19	
$\text{CH}_3\text{CH}_2\text{CHOH}\cdot\text{CH}_2\cdot\text{CH}_3$	116° C.	7-9	
$\text{CH}_3\text{OH}\cdot\text{CH}_2\text{CH}_2\text{CH}_2\text{CH}_3$	131° C.	13-16	
$\text{CH}_3\text{CHOH}\cdot\text{CH}_2\text{CH}_2\text{CH}_3$	114° C.	.5-2	95
$\text{CH}_3\text{OH}\cdot\text{CH}_2\text{CH}_2\text{CH}_2\text{CH}_3$	128° C.	26-29	
$\text{CH}_3\text{CH}_2\text{COH}\cdot\text{CH}_2\text{CH}_3$	102° C.	0-1.5	100

An important requirement of my process is so to regulate the rectification of the casing head gasoline as to separate the first fraction, (which contains undesirable propane and isobutane) with as small a content of desirable normal butane as possible. It is accordingly necessary to reflux isobutane at the beginning of the distillation in order that any normal butane which may have been carried away in the vapors shall be recondensed and returned to the liquid.

While I have described the application of my process to the synthesis of butyl and amyl alcohols from a specific grade of natural gasoline, I do not intend that my process shall be regarded as being limited to the specific example used as an illustration, but that it shall be regarded as covering all modifications or extensions thereof as fall within the hereinafter appended claims.

What I claim as new and desire to secure by Letters Patent of the United States is:

1. In the manufacture of monohydric alcohols having four to five carbon atoms, the steps comprising chlorinating in vapor phase a saturated hydrocarbon obtained from natural gas and having four to five carbon atoms, by heating the hydrocarbon in the presence of chlorine gas and in the substantial absence

of actinic rays and of electric discharge and thereby forming a chlorine derivative thereof containing a substantial proportion of primary monochloride, and hydrolyzing the resulting hydrocarbon chloride by heating in the presence of an aqueous alkaline agent and an ester of a substantially water-insoluble fatty acid and thereby forming corresponding monohydric alcohol of which a substantial proportion is primary normal alcohol.

2. In the manufacture of amyl alcohol, the steps comprising chlorinating in vapor phase saturated pentanes obtained from natural gas, by heating the pentanes in the presence of chlorine gas and in the substantial absence of actinic rays and of electric discharge and thereby forming chlorine derivatives of the pentanes containing a substantial proportion of primary monochlorides of the pentanes, and hydrolyzing the resulting pentane chlorides by heating in the presence of an aqueous alkaline agent and an ester of a substantially water-insoluble fatty acid and thereby forming amyl alcohols of which a substantial proportion is primary normal amyl alcohol.

3. In the manufacture of butyl alcohol, the steps comprising chlorinating in vapor phase saturated normal butane obtained from natural gas, by heating the butane in the presence of chlorine gas and in the substantial absence of actinic rays and of electric discharge and thereby forming a chlorine derivative of the butane containing a substantial proportion of primary mono-chloride of butane, and hydrolyzing the resulting butane chloride by heating in the presence of an aqueous alkaline agent and an ester of a substantially water-insoluble fatty acid and thereby forming butyl alcohol of which a substantial proportion is primary normal butyl alcohol.

In testimony whereof, I have signed my name to this specification.

45 EUGENE E. AYRES, Jr.
